UNITED STATES PATENT OFFICE.

SIGMUND BERGMANN, OF NEW YORK, N. Y.

RHEOSTAT.

SPECIFICATION forming part of Letters Patent No. 395,116, dated December 25, 1888.

Application filed August 23, 1888. Serial No. 283,557. (No model.)

To all whom it may concern:

Be it known that I, SIGMUND BERGMANN, of New York, in the county and State of New York, have invented a certain new and useful 5 Improvement in Regulators for Electric-Light Circuits, of which the following is a specification.

I will describe a regulator embodying my improvement in detail, and then point out the 10 novel features in claims.

The accompanying drawing is a side elevation, partly in section, of a regulator embodying my improvement together with a diagrammatic view of certain resistance-coils and 15 their connections.

Difficulty has been experienced heretofore in operating by hand regulators for maintaining a constant potential in the lamp-circuit, particularly where the same are adapted for 20 throwing both multiple-arc and series resistances into and out of circuit carrying heavy currents. This difficulty has arisen chiefly from the difficulty of obtaining a good electrical contact between the different moving 25 parts of a mechanical switch, from the cumbersomeness of the regulators, and the power necessary to operate them. In my regulator these difficulties are practically overcome.

The main circuit may be of any desired 30 kind and derive its current from a dynamo, as usual.

I have shown a compound regulator—that is to say, one by which both multiple-arc and series resistances may be thrown into and out 35 of circuit. One portion of the regulator, or A, is used for the multiple-arc resistances, and the other, A', for the series resistance. Each of the portions A A' is composed of a series 40 of metallic rings, a—say of iron—forming terminals. These rings are placed one upon the other, and layers, a', of insulating material—as, for instance, asbestos—are interposed between them. When the rings occupy such position, a passage-way, a², which may advantageously be circular, extends vertically 45 and centrally through them. The lower of the rings is provided with a cup-shaped depressed portion, a³, the cavity or recess in which is substantially coincident with the passage a² through the rings a. By means of the 50 passage a² and the depressed portion a³ a receptacle is formed within the terminals. The

lower of the rings a comprised in the portion A of the regulator is provided with a portion, a⁵, extending beyond and to the side of the 55 portion A. To this projecting portion a⁵ is secured a wire, c, leading from the dynamo and constituting an electrode.

Bolts a⁶, properly insulated, extend through apertures in the rings a and secure the latter 60 firmly together and to a base, a⁸, of insulating material, upon which the regulator is mounted. The upper of the rings A in both the portions A and A' are provided with lugs or projections a¹⁰, constituting an electrode, to which is secured one branch, a¹¹, of a line-wire.

B designates pistons or plungers arranged within the passage a², and adapted to be raised and lowered therein. In the example 70 of my improvement shown the plungers or pistons are raised and lowered by means of nuts b engaging the screw-threaded portions of shanks b', extending upwardly from the plungers. The nuts are provided with hand-wheels b², to facilitate their rotation. They are mounted in brackets b³, secured to plates 75 of insulating material, b⁴, upon the tops of the portions A A' of the regulator. The nuts have such a connection with the brackets that 80 they may rotate freely thereon.

I have shown the plungers B as longitudinally corrugated for a distance near their lower ends. I place a liquid conductor—such, for instance, as mercury—in the passages a². 85 When the plungers are lowered, the mercury will be forced upwardly about them. When the plungers are raised, the mercury will descend. Tubes D, of glass, extending upwardly 90 of the sides of the portions A A', and communicating at their lower ends with the passages a², may be used to indicate the height of the mercury about the plungers.

Each of the rings a is provided externally with a binding-post, C. From these binding- 95 posts wires c extend to a number of resistance-coils, f f' f² f³ f⁴ f⁵ f⁶ f⁷ f⁸ f⁹, any desired number of which may be used.

Assuming that it is desired that no resistances be thrown into the circuit, both the 100 plungers B are lowered sufficiently to cause the mercury or other liquid conductor to rise in such manner as to bring all the rings a into electrical circuit. The current will then

short-circuit on the portion A of the regulator, and will pass directly from the wire e to the wire a^{11} . If the first step be now taken, the plunger B of the series portion, or A' of the regulator, is permitted to remain in its lowermost position, and the plunger B of the multiple-arc portion, or A of the regulator, is elevated until the mercury falls below the upper of the rings a , thereby cutting the latter out of circuit. Current will then flow from the wire e through all of the remaining rings a , below the upper ring, along their several connecting-wires c to the resistance-coils f^2 f^3 f^4 , &c., out through circuit-wires c', connecting with the other ends of the resistance-coils and with the terminals a of the portion A' of the regulator, and thence to the line-wire a^{11} . The second and each succeeding step in the operation of the multiple-arc resistances is like that just described. At each step the plunger is raised sufficiently to lower the mercury below another of the rings a , thereby cutting such ring, and consequently the resistance coil or coils with which it is electrically connected, out of circuit. When therefore the plunger has been elevated so far that only the lower of the rings a and its coacting resistance coil or coils are in circuit, the greatest multiple-arc resistance will have been thrown into the circuit. If now it is desired to throw series resistances into the circuit, the plunger of the portion A is maintained elevated and the elevation of the plunger of the portion A' is commenced. When the mercury or other liquid conductor has sunk below the upper of the rings in the portion A', the current can no longer pass directly to the line-wire a^{11} . It therefore returns along the wire c' leading to the coil f, thence along the coil f and the wire c in connection therewith to the upper of the rings a of the portion A of the regulator, and thence to the line-wire a^{11} . It will be readily seen that as the plunger in the portion A' is still farther elevated, so as to cause the mercury to fall below the rings a successively, additional series resistances will be thrown into circuit, because the current at each step is returned through a number of coils connected in series.

I wish it to be understood that by the term "piston" or "plunger" in reference to the part by which the mercury or other liquid conductor is caused to close or open circuit at the terminals I mean any of the known equivalents for a piston or plunger.

I further wish it understood that I do not limit the use of the moving fluid conductor by piston or plunger, as set forth. The piston or plunger may be stationary, and the liquid conductor caused to rise or fall by the raising or lowering of a reservoir connected to the cistern by flexible pipe; or the height of the liquid conductor may be varied by pressure or suction, by which the mercury or liquid conductor is caused to close or open the circuit at the terminals.

By my improvement I provide an easily-operated and yet effective regulator, and withal one that is compact and not liable to derangement.

What I claim as my invention, and desire to secure by Letters Patent, is—

1. The combination, with an electric circuit, of a regulator comprising a number of resistances, a number of terminals in electrical connection with said resistances, and a liquid conductor within said terminals for bringing said resistances into and out of circuit, substantially as specified. 75 80

2. The combination, with an electric circuit, of a regulator comprising a number of resistances, a number of terminals in electrical connection with said resistances, a liquid conductor within said terminals for bringing said resistances into and out of circuit, and means, substantially such as described, for causing the liquid conductor to close or open circuit on said terminals, substantially as specified. 85

3. The combination, with an electric circuit, of a regulator comprising a number of resistances, a number of terminals constituting a receptacle for a liquid conductor and electrically connected to the resistances, and means, substantially such as described, for raising 95 and lowering the liquid conductor in the receptacle to bring the various terminals and resistances into or out of circuit, substantially as specified. 90

4. The combination, with an electric circuit, of a regulator comprising a number of resistances, a number of terminals constituting a receptacle for a liquid conductor and electrically connected with said resistances, and a piston for causing variations in the height of the liquid conductor to throw resistances into or out of circuit, substantially as specified. 100 105

5. The combination, with an electric circuit, of a regulator comprising a number of resistances, two receptacles for a liquid conductor, 110 each comprising a number of terminals in electric communication with said resistances, one of said sets of terminals being connected to said resistance-coils in multiple arc and the other set in series, and means for varying 115 the height of the liquid conductors in the receptacles to bring the resistances successively into or out of circuit, substantially as specified. 120

6. The combination, with two electrodes, of two receptacles for liquid conductors, each comprising a number of terminals, resistances in circuit with said terminals, and pistons for varying the height of the liquid conductors in the receptacles, one of said electrodes being connected to direct current to one of said sets of terminals only, and the other electrode being connected to receive current from both said sets of terminals, substantially as specified. 125
